WIRE TONGS

Joseph J. Habeck, Milwaukee, Wis.

Application April 30, 1947, Serial No. 744,964

5 Claims. (Cl. 294—99)

1

My invention relates to improvements in wire tongs.

The object of my invention is to provide inexpensive and conveniently applicable tongs, particularly adapted for culinary purposes, such as the lifting of pickles, olives, or similar articles from receptacles, and for turning articles that are being fried, etc., but also adapted, when made of heavier wire, to be used for other purposes.

In the drawings:

Figure 1 is a perspective view of my improved wire tongs, with dotted lines indicating their gripping position.

Figure 2 is a fragmentary view showing modified gripping members.

Figure 3 is a similar view showing a second modification, in which the gripping members are spoon shaped.

Figure 4 is a sectional view drawn to line 4—4 of Figure 3.

Figure 5 is a view similar to Figure 2, showing a third modification.

Like parts are identified by the same reference characters throughout the several views.

A single piece of resilient wire is intermediate-ly folded upon itself to form an eye-shaped hanger 10 and a pair of legs A and B having divergent free end portions 11 and 23 which constitute the gripping arms of the tongs. Between these gripping arms and the eye-shaped hanger 10 the leg A has a straight portion 13, a laterally extending U-shaped or V-shaped handle portion 14, and another straight portion 15 connected with the tong arm 11.

In the construction illustrated, the leg B extends from the eye 10 in the form of an open helical spring coil 16 having about eight turns around the portion 13 of the member A. It is then closely coiled at 17 about the portion 13 at its junction with the laterally extending handle 14 and extends laterally in the opposite direction in the form of a similar U-shaped, or V-shaped, handle 19, on the return side of which it is again closely coiled about the portion 15 at its junction with the handle 14. From the coil 16 the leg B has a portion 21 extending parallel to the portion 15 to a point where it is for a third time closely coiled at 22 about the member 15 at its junction with tong arm 11. From this coil 22 the member B extends in the form of a gripping tong arm 23 normally divergent from the tong arm 11.

The close coils 17, 20 and 22 serve as pivotal connections between the legs A and B at their junction with the tong arms 11 and 23 and at both sides of the members 14 and 19. The

2

handles 14 and 19 are normally obliquely divergent, and, when pressed together, toward each other, as indicated by dotted lines in Figure 1, will swing the tong arms 11 and 23 toward gripping position. The free end portions of the arms 11 and 23 are curved to allow their extremities to be brought into point contact with each other, as shown by dotted lines in Figure 1, when an object to be lifted is not interposed.

10 The resilience of the coil 16 restores the handle portions 14 and 19 and the tong arms 11 and 23 to their normal spread position as soon as manual pressure upon the handles 14 and 19 is released.

15 In Figure 2 I have illustrated tong arms 11a and 23a, the extremities of which are provided with eye-shaped loops 25 and 26 respectively.

In Figures 3 and 4 I have illustrated a further modification in which the tong arms 11b and 23b

20 have spoon-shaped extremities 27 and 28, and in Figure 5 the free ends of the tong arms are forked as shown at 29. It will therefore be understood that the extremities of the tong arms may have any desired shape in accordance with 25 the character of the articles to be gripped or lifted, and in Figure 5 the tips of the gripping arms are forked as indicated at 32.

I claim:

1. Tongs composed of a single piece of resi-30 lant wire bent upon itself intermediate of its ends to form a pair of legs having oppositely extending handle portions, and divergent end portions adapted to serve as gripping arms, one of the legs being openly coiled about the other 35 between the intermediate bend and the gripping arms and closely coiled about said other leg at each side of the handle arms and at its junction with its gripping arm to provide pivotal connections between the legs.

2. Tongs composed of a piece of wire bent to 40 form a pair of legs having normally divergent gripping arms and provided with obliquely divergent handles, said legs being pivotally connected with each other on opposite sides of the handles, and adjacent their junction with the gripping arms, and one of the legs having a resilient portion coiled helically about the other leg to place the gripping arms under spring tension normally holding them in divergent position.

3. Tongs comprising a pair of wire legs connected with each other at one end and having normally divergent gripping arms at the other end, each of said legs having an intermediate handle normally obliquely divergent from the handle on the other leg, said legs being pivotally

connected with each other on opposite sides of the handles and adjacent to the gripping arms, one of the legs being formed as an open helix about the other leg and adjacent the connections between the legs to form spring means for normally holding the handles and gripping arms in widely divergent positions, said legs, handles, and gripping arms being composed of a single piece of wire folded upon itself at the end distant from the gripping arms.

4. Tongs composed of a single piece of resilient wire intermediately folded upon itself to form an eye-shaped hanger and one leg portion provided with a laterally extending loop adapted to serve as an operating handle and a curved laterally extending free end adapted to serve as a gripping arm, said leg being otherwise substantially straight, and the other leg having an open helical coil about a straight portion of the first mentioned leg, an operating handle similar to that of the first mentioned leg and obliquely divergent therefrom and a plurality of close coils about the first mentioned leg, adapted to pivotally connect the legs for oscillation about their axes in opposition to the resilient urge of the helically coiled portion.

5. Tongs composed of a single piece of resilient wire folded upon itself intermediate its ends

10
15

to form a hanger and with one leg portion provided with a lateral loop adapted to serve as an operating handle and a lateral free end adapted to serve as a gripping arm, said leg being otherwise substantially straight, and with another leg portion having an open helical coil about a straight portion of the first said leg and provided with a lateral loop adapted to serve as an operating handle and obliquely divergent from the handle of the first said leg portion and having a plurality of coils closely about the first mentioned leg for pivotally connecting the legs for oscillation about their axes, the open coil portion of the second said leg urging the legs about their axis for separating the gripping arms.

JOSEPH J. HABECK.
